Primary Examiner — Paula Allen Greene

(57) **CLAIM**

The ornamental design for a desktop-type mini microphone, as shown and described.

DESCRIPTION

FIG. 1 is a top perspective view of a desktop-type mini microphone showing my new design; and

FIG. 2 is a front view thereof;

FIG. 3 is a rear view thereof;

FIG. 4 is a left elevational side view thereof;

FIG. 5 is a right elevational side view thereof;

FIG. 6 is a top elevational view thereof; and,

FIG. 7 is a bottom elevational view thereof.

The bottom part of the cable is drawn broken away in the Figures for ease of illustration.

1 Claim, 6 Drawing Sheets
